UNITED STATES PATENT OFFICE

LOUIS D. PEIK, OF MISHAWAKA, INDIANA, ASSIGNOR TO THE AMERICAN FOUNDRY EQUIPMENT COMPANY, OF NEW YORK, N. Y., A CORPORATION OF DELAWARE

MULTIPLE BLAST NOZZLE

Application filed May 28, 1930. Serial No. 456,338.

The invention relates to the art of sand blasting or scrubbing rough surfaced objects such as castings, sheet metal and the like.

5 According to the invention a multiple nozzle sand blast gun is provided comprising a main conduit which directly supports the several nozzles and a second or auxiliary conduit or manifold. A source of abrasive such as sand and carrying a fluid such as air is connected to the main conduit and a source of clean fluid is connected to the auxiliary conduit. A plurality of connecting conduits connect the main and auxiliary conduits, 10 these conduits being substantially in line with the several nozzles. If desired, the mixture of air and abrasive may be supplied to one end of the main conduit and the clean air only may be supplied to the auxiliary 15 conduit at a point intermediate the ends. In some cases it may be desirable to offset the connecting conduits slightly from the center lines of the nozzles in a direction contrary to the direction of flow of the air and abrasive 20 in order to improve the blast and to prevent undue wear on the manifold parts. The provision of the auxiliary clean air serves to boost the blast of abrasive which normally would issue from the nozzles, creating a more 25 intense blast and also assists materially in equally distributing the blasts from the several nozzles of the manifold.

The invention also consists in certain new and original features of construction and 30 combinations of parts hereinafter set forth and claimed.

Although the novel features which are believed to be characteristic of this invention 35 will be particularly pointed out in the claims appended hereto, the invention itself, as to its objects and advantages, the mode of its operation and the manner of its organization may be better understood by referring 40 to the following description taken in connection with the accompanying drawing forming a part thereof, in which

Fig. 1 is a view of one form of multiple abrasive blast gun according to the invention;

Fig. 2 is a section on the line 2—2 of Fig. 1;

Figs. 3 and 4 are longitudinal sections taken through the ends of the main conduit; and

Fig. 5 is a view illustrating a slightly modified form of multiple gun.

In the following description and in the claims parts will be identified by specific names for convenience, but they are intended to be as generic in their application to similar parts as the art will permit.

Like reference characters denote like parts in the several figures of the drawing.

In the drawing accompanying and forming part of this specification, practical commercial embodiments of the invention are shown, but as such illustrations are primarily for purposes of disclosure, it will be understood that the structure may be modified in various respects without departure from the broad spirit and scope of the invention as hereinafter defined and claimed.

Referring now to the drawing, and more particularly to Figs. 1 to 4, the sand blast gun comprises a straight line main manifold or conduit 10 supporting a plurality of sand blast nozzles 11. An auxiliary manifold or conduit 12 is provided which has a supply pipe 13 connected to a point intermediate its ends. A plurality of connecting conduits of small diameter connect the auxiliary conduit 12 and main conduit 10 and are in substantial alignment with the axes of the nozzles 11 as shown.

The connecting conduits 14 may be suitably connected to the conduits 10 and 12 by a welding process and the nipple 15 may also be connected to the conduit 10 by a suitable welding process. The fitting 16 is threaded onto the nipple 15 and the fitting 17 is provided for connecting the nozzle tip 18 to the fitting 16. The main manifold 10 may be in the form of a suitable pipe and its end may be stopped by a flat disc 19 suitably welded in position as shown. At the other end of the manifold 10 the nipple 20 may be suitably welded in position and the flange 21 may be threaded onto the fitting 20 as shown.

It will be understood that a source of air

and suitable abrasive, such as sand, will be connected to the fitting 21, the air being under pressure and carrying along the sand in suspension. A suitable source of clean air alone 5 will be connected to the supply pipe 13. It will be noted that the mixture of sand and air fed to the fitting 21 is mixed or carburetted before delivery thereto.

If desired, the modified form shown in Fig. 10 5 may be used. In this form a pipe for supplying clean air is denoted by 33, the auxiliary manifold by 32, main manifold by 30, connecting conduits by 34 and nozzles by 31. As shown, the connecting conduits 34 are 15 displaced from the axes of the nozzles 31 in a direction toward the supply end of the conduit 30 to which the mixture of air and abrasive is supplied.

The auxiliary conduit or booster line on the 20 back of the main nozzle manifold assists materially in distributing the abrasive equally among the several nozzles. Without the booster connections it has been discovered that the nozzles furthest from the inlet side 25 of the manifold eject considerably more sand than the nozzles near the entrance. The auxiliary supply of clean air through the booster connections seems to equalize the pressure within the main manifold and counteract 30 the incoming abrasive laden air currents to a certain extent, in such manner as to create a condition of balancing saturation of sand by which equal blasting is obtained from the several nozzles. In addition to assisting in the equal distribution of abrasive 35 from the several nozzles, the booster connections increase the velocity through the orifices of the nozzles, thus building up the efficiency of the blast. The expansion of the air 40 as it leaves the nozzle orifices is increased by the use of the booster and thus the blast is intensified and greater velocity is imparted to the sand particles.

Some variation in the position of the connecting booster conduits with respect to the axes of the nozzles may be permitted, and in fact may be desirable on smaller diameter manifolds in which the velocity of the current of abrasive laden air is greater. The 45 blast is sometimes considerably improved by setting the booster off from the center toward the incoming stream as explained above in connection with Fig. 5. On larger sizes of manifolds where the velocity of the incoming 50 blast of sand laden air is slower, the booster connections may be placed directly over the center. If the position of the connecting booster conduits with respect to the axes of the nozzles is not proper, holes may eventually 55 be blown through the main manifold at the connection of the nozzles thereto due to the scrubbing or abrasive action of the sand on the metal of the manifold itself.

It will be understood that the sizes and 60 diameters of the various conduits and pipes

must be proper and in proper relation to the pressures used in order to obtain maximum efficiency. For instance, if the connecting conduits 14 and 34 are too large or if the pressure of the auxiliary air supply is too high, this may have the detrimental effect of backing 70 up the sand flow in the main conduit.

In use, the multiple nozzle gun may be stationary and the work which is indicated by 75 22, Fig. 1, may be movable or vice versa. In Fig. 1 the work is indicated as being in the form of a flat sheet and the blast of abrasive is illustrated as impinging upon the sheet and spreading out as it hits the sheet, exerting 80 a cleaning action on it. It will be understood that the multiple nozzle manifold may be disposed in a vertical position or a horizontal position, or in fact any desired position, and that other kinds of work, such as pipes, may be subjected to the action of the gun and scrubbed and cleaned thereby.

While certain novel features of the invention have been shown and described and are pointed out in the annexed claims, it will be understood that various omissions, substitutions and changes may be made by those skilled in the art without departing from the 90 spirit of the invention.

What is claimed is:

1. In an abrasive blast gun, a main conduit 95 for supplying a carburetted mixture of abrasive and a carrying fluid, a nozzle projecting laterally from main conduit and an auxiliary conduit connected to said main conduit for supplying an auxiliary fluid to said nozzle, said auxiliary conduit being substantially in line with said nozzle but offset from the axis of said nozzle in a direction opposite to the direction of flow of the abrasive and carrying fluid.

2. A multiple abrasive blast gun comprising a main conduit having an inlet opening for a supply of carburetted abrasive and air, an auxiliary conduit alongside said first conduit, a plurality of nozzles spaced along said main conduit and connected thereto, and projecting laterally therefrom, and connecting conduits extending from said auxiliary conduit to said main conduit substantially in line with said nozzles, respectively, said second conduit having an inlet opening for clean air, said connecting conduits being spaced slightly from said nozzles towards the inlet opening of said auxiliary conduit.

3. A straight line multiple abrasive blast gun comprising a main, straight conduit having an inlet opening at one end for a supply of carburetted abrasive and carrying fluid, an auxiliary straight conduit alongside said first conduit, a plurality of nozzles spaced along the length of said main conduit and connected thereto and projecting laterally therefrom, and connecting conduits extending from said auxiliary conduit to said main conduit substantially in line with said noz- 125

zles, respectively, said auxiliary conduit having an inlet opening midway its length for clean fluid, said connecting conduits being spaced slightly from said nozzles towards the inlet opening of said main conduit.

5 In testimony whereof I have hereunto set my hand.

LOUIS D. PEIK.
